CLAIM

The ornamental design for a ball and strap system, as shown and described.

DESCRIPTION

FIG. 1 is a top, front and side perspective view of a first embodiment of a ball and strap system embodying my new design.

FIG. 2 is a bottom, back and side perspective view thereof.

FIG. 3 is a back view thereof.

FIG. 4 is a front view thereof.

FIG. 5 is a right side view thereof.

FIG. 6 is a left side view thereof.

FIG. 7 is a top view thereof.

FIG. 8 is a bottom view thereof.

FIG. 9 is a top, front and side perspective view of a second embodiment of a ball and strap system embodying my new design.

FIG. 10 is a bottom, back and side perspective view thereof.

FIG. 11 is a back view thereof.

FIG. 12 is a front view thereof.

FIG. 13 is a right side view thereof.

FIG. 14 is a left side view thereof.

FIG. 15 is a top view thereof; and,

FIG. 16 is a bottom view thereof.

The broken lines are included for the purpose of illustrating stitching and seams that form no part of the claimed design.

1 Claim, 12 Drawing Sheets
